UNITED STATES PATENT OFFICE.

DAVID E. HUNTER, OF MUSKEGON, MICHIGAN, ASSIGNOR TO SHAW-WALKER COMPANY, OF MUSKEGON, MICHIGAN, A CORPORATION OF MICHIGAN.

POSTING TRAY.

Application filed July 26, 1922. Serial No. 577,564.

To all whom it may concern:

Be it known that I, DAVID E. HUNTER, a citizen of the United States, and a resident of Muskegon, in the county of Muskegon 5 and State of Michigan, have invented certain new and useful Improvements in Posting Trays, of which the following is a specification.

This invention relates to improvements in 10 posting trays, a term applied to devices used in connection with bookkeeping machines as a holder or rack for the entry sheets, and taking the place of the ordinary ledger or other books of account.

15 With the advent of the bookkeeping machine, the posting tray was adopted as a desirable and necessary expedient for facilitating the handling of the entry sheets, and to otherwise reduce the time and labor involved in the more mechanical bookkeeping 20 systems. In a few words, a posting tray is a portable device to be used in conjunction with a bookkeeping machine and forming a permanent and readily accessible 25 holder for the ledger or record sheets.

The object of the invention is to incorporate in a device of the character described, 30 certain improved features of construction calculated to increase the practicability, ease of operation and general utility of the posting tray as part of a mechanical bookkeeping system. The various improvements will be pointed out as the device is described and 35 in connection with the accompanying drawings, wherein,

Fig. 1 is a view in front elevation of the posting tray,

Fig. 2 is a view in side elevation of the posting tray,

Fig. 3 is a top plan view,

Fig. 4 is an enlarged detail view in vertical section taken on line 4—4 of Figure 2, showing the tray slightly elevated from the pedestal,

Fig. 5 is an enlarged detail plan view of the front portion of the tray, with parts shown in section as taken on line 5—5 of Figure 1, and

Fig. 6 is an enlarged detail elevation of 50 the tray partly in section, taken on line 6—6 of Figure 5.

In general, the preferred embodiment of the invention, comprises a pedestal type of stand 1, supporting the posting tray 2, the latter resting upon the stand so that it may

be lifted off and deposited in the vault, for safe keeping when not in use. The stand 1, and in fact the complete structure is preferably made of sheet metal, although it could also be reproduced in wood. The stand 1, comprises a single tubular square pedestal or column having four radiating feet 3, mounted on casters 4;—the column is preferably made up of telescopic sections 1^a and 1^b with suitable adjusting members such as screws 5, 5 in order that the height of the stand may be adjusted to suit the convenience of the operator. At the upper end of the pedestal is mounted a rectangular frame or base 6, for the posting tray proper 70 2. The base 6 is constructed of channel side and end bars 7 and 8 respectively, joined together to form an open rectangular frame, the end portions 7^a, 7^a of the side bars being bent over the end bars, and secured by 75 means of screws 9. Other channel bars 10, 10 extend lengthwise of the frame, and spaced inwardly from the side bars, 7, 7, being connected at their ends to the end bars 8, 8, by said screws 9, and are screwed 80 to the pedestal 1^b by bolts 11, 11, (Figure 4). Along the side edges of the base, are upstanding flanges 12, 12, preferably formed by bending the inner edges of the 85 side channel bars 7, 7 upwardly. These flanges serve to engage the tray to hold it in position, and against sliding upon the base 6.

The tray 2, is a frame of somewhat the same construction as the base, just described, 90 consisting of channel-shaped end bars, 13, 13, and bottom plates 14, extending the full length of the frame and screwed at their ends to said end bars thereby forming a 95 rigid structure.

Along the sides of the frame are side plates, 15, 15, having their lower marginal portion bent inwardly to form flanges 15^a, 15^a, adapted to have abutting engagement 100 with the vertical flanges 12, 12 of the base 6. At the ends of the side plates are fixed channel shaped end sections 16, 16, extending at right angles thereto, and having telescopic engagement with the end bars 13. These side plates are adapted for adjustment relative to the end bars 13, 13, through the medium of sliding engagement between 105 said bars and the telescopic end sections 16, 16, these parts being secured in two or more positions of adjustment by bolts 17, 110

passing through a bolt hole in the end section and one of several bolt holes 18, spaced longitudinally at the ends of said bars (Figure 4).

- 5 Extending along the sides of the tray above the side plates 15, 15, are side bars, 19, secured at their ends to the side plates. These bars serve as handles for lifting the tray. It is to be observed that the side 10 plates project but a short distance above the level of the upper portions of bottom plates 14, and thus the sides of the tray are comparatively open, thereby permitting the light to enter freely, so that the sheets 15 may be read distinctly without removing them from their places.

The bottom wall plates 14, form the supporting track for the sheets, guides and follower plates, hereinafter to be described, 20 it being noted that said follower plates are offset slightly to the left of the center of the tray, for reasons better understood in a general discussion to follow. Extending lengthwise of the bottom plates are central 25 channels consisting of side walls 20, 20, bottom walls 21, 21, and vertical flanges 22, 22, extending on either side of a slot extending the length of said channel. Along either side of the channels are formed rails 30 23, 23, preferably covered with strips of cork 23^a or like material which will permit the sheets to stand on edge without slipping.

The covered rails 23 form the bearing 35 surface for the file of entry sheets 24, and guide cards 25 which are arranged alphabetically in the manner common to filing systems, and held in upright position between two follower plates 26 and 27 at front and rear of the sheets respectively. The 40 guide cards 25, are secured to the tray by means of a slide rod 28, extending lengthwise within the channel in the bottom wall 14, and which passes through eyelets formed in tabs 25^a of the guide cards in the usual 45 manner.

The follower plates are movable lengthwise of the tray, to allow for expansion or contraction of the contents of the file, and for a further purpose presently to be pointed 50 out, namely, to close and compress the sheets when the tray is not in use, in the same manner that one would close a book.

The rear follower plate 27, will be described first. It consists of a flat metal 55 plate, adapted to be stood in an upright position or to be tilted backward; moreover, it may assume either position, at any point along the track by the provision of the following devices:—Along the track 60 just inside of the rails 23 are series of slots 29 in bottom plates 14 arranged in corresponding pairs on opposite sides of the trough. These slots are formed in the vertical side walls 20, of the channels and are 65 extended into the bottom walls of the same

as will better be understood from the following:

As shown in Figures 5 and 6 each slot, 70 consists of a transverse portion 29^a of uniform width, cut in the rail 23 and extending inwardly from the edge of the channel to the cork strips 23^a, a diverging portion 29^b, in the vertical wall 20, and an inner portion 29^c formed in the bottom wall 21.

The horizontal slot portions 29^a and 29^c 75 form continuations of the vertical slot 29^b, and while the rear edge of all lie in the same vertical plane, the front margin of the latter inclines forward from top to bottom at an angle of substantially thirty 80 degrees (30°) to the vertical as clearly shown in Figure 6.

The follower plate 27, is provided along its lower edge with a heavier base plate 30, slightly narrower than the plate itself, 85 and shaped along its lower edge to form triangular shaped tongues 30^a, at the lower ends thereof which project beyond the lower edge of the plate. Just above the tongues and fixed to the back side of the base plate 90 30, is a cross bar 31, which serves to support the tongues in the slots and to engage the rails 23, as a rest for the plate.

As heretofore suggested the plate 27, is 95 adopted to be supported in either an upright or tilted position: In order to obtain the upright position, the plate is inserted vertically into the slots 29^c in the rails, the tongues being guided into the slots 29^b in the bottom plates in vertical alignment therewith, with the ends of the bar 31 resting at its ends upon the rails 23, thus the engagement between the base plate 31 and vertically spaced slots hold the plate in upright 100 position as closely shown in dotted lines in 105 Figure 6. To shift the plate into tilted position (see full lines Figure 6), the same would be lifted until the tongues disengage the lowermost slots 29^c, thereby permitting the plate to tilt back until the lateral margins of the tongues engage the inclined front edges of the vertical slots 29^b, with the bottom edges of the tongues resting on the bottom wall 21, forwardly of the slots 29^b. Thus the rear follower plate can be moved 110 to any position along the track and inserted in either position or shifted from one to the other, as the operator desires, a handle 32 being applied to the back of the plate for 115 this purpose.

The forward follower plate 26 is mounted in an entirely different manner, yet designed to be tilted and shifted along the track as is the rear follower plate, although its path of movement is comparatively short, being confined to the forward end portion of the track.

The plate 26 is pivotally mounted along its lower edge to a sliding carriage comprising an angular plate 32, having integral 120 125 130

sleeves 33, 33 which are mounted on a pair of slide rods 34, 34 mounted beneath the carriage and extending longitudinally of the channel, the front ends of the rods being 5 anchored in a bar 35 secured against the front end frame member, and the rear ends in angle bars 36, 36, mounted upon the side walls 21 of the channel.

The angular plate consists of an upper 10 vertical portion 32^a spaced forwardly of the follower plate 26, a lower vertical portion extending below the track, and carrying the sleeves 33, and an intermediate horizontal portion 32^c, whereby the upper portion 32^a 15 is offset forwardly of the plate 26, which is mounted at the rear edge of the portion 32^c by means of a hinge 37.

In order to lock the carriage against free movement in a forward direction, a locking 20 device is provided, consisting of a lever arm 38, passing through a slot in the horizontal portion 32^c of the plate 32, and provided at its lower end with an opening through which one of the slide rods 34 extend, (Figure 6). 25 A flat spring 39 secured to the plate 26, bears against the lever, forcing it forward, so that it normally grips the rod preventing the forward movement of the carriage, except when the upper end is pressed against 30 the spring by the thumb, thus releasing the lever.

Hinged to the front face of the plate 27 is a brace 40, consisting of a small plate bent to provide marginal flanges and notches 40^a 35 formed at the ends of the flanges. The plate is pivoted horizontally to a hinge plate 41, fixed to the follower plate 26 just above the level of the upper edge of the upper portion 32^a of the plate 32 of the carriage. The 40 brace plate 40, normally rides on the top edge of the relatively fixed plate 32, so that by pressing forwardly on the follower plate 26, until it assumes a vertical position, the notches 40^a drop into engagement with the 45 edge of the plate 32, thus locking the follower plate in vertical position. Pressing upwardly at the end of the brace plate, releases the follower plate, allowing it to fall forwardly into tilted position against the 50 edge of the plate 32.

In operating the posting tray it will be understood that the contents, consisting of a large number of entry sheets and guides similar to any filing system, should have sufficient excess space from front to rear so that in going through the file the sheets may be turned forward, one after the other, with a V-shaped crevice between, in order that the operator may remove any sheet without losing the place where the sheet is to be replaced. This then, is accomplished by separating the follower plates a greater distance than the thickness of the compressed sheets, and also tilting them away from the vertical. 60 Thus the rear plate would incline rearwardly

and the front plate forwardly, and the contents be similarly divided at any point into rearwardly and forwardly leaning portions, which retain their positions naturally, thereby permitting the operator to manipulate 70 the sheets freely. The cork-faced rails aid in this by preventing the slipping of sheets.

As already suggested the rear follower plate 27, is movable to permit the expansion 75 of the file and also to compress the file preparatory to closing it, although usually the rear plate is retained in one position and the entire compression and expansion of the file obtained by sliding the front plate in or out, the distance of travel of its carriage. To 80 expand the file for use, the lever, 38, is pressed thus releasing the carriage so that it may be drawn forward. Merely pushing the carriage rearwardly against the contents of the file effects a partial compression, but 85 only partially, because the plates would ordinarily be tilted, hence the first operation in closing the file is to straighten the rear plate by shifting it into vertical position, thus allowing the lugs 30^a to drop into the 90 horizontal slots 29^a, in the bottom wall 21, of the channel. The front plate is straightened as the final operation in closing the file, this being accomplished in manner already described. 95

The straightening of the follower plates applies a uniform binding pressure to the contents, thereby preventing their displacement or disarrangement in moving the tray from place to place, or in handling the same 100 when not in use.

The device herein disclosed combines numerous advantageous features, such as security in the binding of the contents, ease and convenience of handling the individual sheets, and otherwise promoting a systematic method of bookkeeping. Other advantages may be mentioned, among which are, the adjustable width of the tray which permits the use of various sizes of sheets, without the expense of replacing the device with one of larger size; the open side walls which permit the lower portions of the sheets to be easily read without removing the same from the tray, and finally the open or skeleton structure employed throughout which tends toward lightness in weight and more sanitary and cleanly conditions, there being little or no opportunity for the collection of dust, and such articles as pins, paper fasteners, etc. 115

Having described the preferred embodiment, I now claim my invention subject to the right to employ such departures and modification as may be adopted, without departing from the spirit of the invention. 125

1. In a device of the character described, the combination of a tray having a central longitudinal channel and a follower plate 130 provided with tongues at its lower edge

adapted to engage within slots arranged along said channel and consisting of connected portions formed in the vertical and horizontal walls along the sides of said channel, said horizontal portions acting to retain the plate in upright position, and said vertical portions being of tapered form to permit said plate to be tilted when said tongues are released from one of said horizontal portions.

2. In a device of the character described, the combination of a tray having contents-supporting rails and an intermediate longitudinal channel provided with pairs of slots spaced apart along opposite sides of said channel, each pair of slots consisting of tapered vertical portions and straight upper and lower horizontal portions, and a follower plate adapted to be retained in said pairs of slots and adjustable to engage the vertical portions and the upper horizontal portions to assume a tilted position, and to engage both of the horizontal portions to assume an upright position.

3. In a device of the character described the combination of a tray, having contents-supporting rails and an intermediate channel and a follower plate adapted to be supported to a predetermined point by means of slots formed in the walls of said channel, and arranged in pairs, each pair consisting of tapered slots in the side walls and straight transverse slots in said rails and the bottom wall of said channel, said plate being held in vertical position when engaging said straight slots and in tilted position when released from the lower straight slot.

4. In a device of the character described the combination of a tray, a sliding carriage mounted on said tray, a follower plate pivotally mounted on said carriage and a hinged brace mounted on said plate and adapted to engage said carriage to hold said plate in vertical position.

5. In a device of the character described the combination of a tray having a contents-supporting track, a carriage having a limited slideable movement along said track, a follower plate pivotally mounted on said carriage, the same having an upright plate for supporting said follower plate in tilted position, and means for releasably bracing said plate in vertical position.

6. In a device of the character described the combination of a tray, a carriage slideable on said tray, a follower plate hinged at its lower edge to said carriage, a manually releasable member for locking said carriage from movement in one direction and a hinged brace mounted on said plate and adapted to engage said carriage to hold said plate in upright position to compress the contents of the tray.

7. In a device of the character described the combination of a pedestal, a tray re-

movably supported upon said pedestal, and comprising a contents-supporting track having rails of pliable material along said track, front and rear follower plates adapted to be tilted in opposite directions for opening the contents of the tray, one of said plates being slideable to compress said contents, and provided with releasable locking means acting automatically to lock said sliding follower plate in the position of maximum sliding movement to compress said contents and a hinged brace mounted on said plate and a member slideable with said plate and coacting with said brace to hold the same in vertical position in the act of compressing the contents by exerting pressure thereon.

8. In a device of the character described the combination of a tray, having a contents-supporting track extending lengthwise thereof, and consisting of rails and an intermediate channel, front and rear follower plates, rods secured at the forward end portion of said channel, a sliding carriage mounted upon said rods, and hingedly supporting the front follower plate, and a normally releasable spring-pressed locking member mounted on said carriage and engaging one of said rods, whereby said carriage is held from movement in a forward direction.

9. In a device of the character described the combination of a tray, having a contents-supporting track extending lengthwise thereof, and consisting of rails and an intermediate channel, front and rear follower plates, rods secured at the forward end portion of said channel, a sliding carriage mounted upon said rods, and comprising a plate bent to provide an upstanding portion and a lower portion extending into said channel, said front plate being hinged to said carriage in spaced relation to said upstanding portion, and adapted to be supported thereby in tilted position, a brace connected to said plate and adapted to engage said upstanding portion to support said plate in upright position, and a locking member carried by said carriage and engaging said rod to lock said carriage from forward movement.

10. In a device of the character described the combination of a tray, having a contents-supporting track provided with slots therealong, a rear follower plate adapted to be supported in tilted or upright position in said slots, a carriage slideably mounted adjacent the forward end of said track, a front follower plate hinged to said carriage, a member on the carriage for supporting said plate in tilted position and a coacting brace for supporting said plate in upright position, and means for locking said carriage in a predetermined position against forward sliding movement.

11. In a device of the character described

the combination of a tray, consisting of side and end frame members, a contents-supporting track extending between said end frame members and fixed thereto, said side frame members being provided with end portions overlapping said end frame members, fastening means for adjusting the side frame members transversely to vary the width of said tray, and rails extending along said side frame members and spaced above the level of said supporting track.

12. In a device of the character described the combination of a tray, consisting of side

and end frame members, and a contents-supporting track having rails surfaced with pliable material, said track being fixed to said end members, and said side members having adjustable connection with said end members, for increasing or decreasing the width of the space on either side of said track, and rails extending above said side frame members, and forming handles for said tray.

In witness whereof, I hereunto subscribe my name this 16th day of June, A. D. 1922.

DAVID E. HUNTER.
